UNITED STATES PATENT OFFICE.

WILLIAM GEORGE MOORE, OF WARREN, OHIO, ASSIGNOR TO THE AETNA FOUNDRY
AND MACHINE COMPANY, OF WARREN, OHIO.

APPARATUS FOR CLEANING TIN PLATES.

1,138,134.

Specification of Letters Patent.

Patented May 4, 1915.

Application filed July 27, 1914. Serial No. 853,398.

To all whom it may concern:

Be it known that I, WILLIAM GEORGE MOORE, a citizen of the United States, residing at Warren, in the county of Trumbull and State of Ohio, have invented certain new and useful Improvements in Apparatus for Cleaning Tin Plates, of which the following is a specification.

The invention relates to the means employed for circulating the material used in cleaning tin plates after they leave the bath. It is well known to those familiar with the art of making tin plates, that it is necessary to clean the plates after they are extracted from the tinning bath, owing to the extraneous matter that adheres to said plates. It is also desirable to cool the plates before they pass to the cleaning rolls. The cleaning medium commonly used consists of a mixture, the principal ingredients of which are coarse bran and a light oil, this is deposited on the rolls and plates as they are passed through the cleaning roll mechanism. It is brushed off by said rolls into a hopper, and is used over and over again, the same batch being utilized in the cleaning of a large number of plates. The common practice is to carry the mixture from the hopper by means of an endless bucket-chain elevator to a point above the cleaning roll mechanism, and discharge it through a chute onto the rolls. In order to accomplish the desired result, in the method now in common use, it is necessary to employ a mechanism comprising coöperating elements that are expensive to install and to keep in repair, in comparison to the installation and up-keep of the improved apparatus.

The objects of this invention are the provision of economical, durable and efficient means for effecting a free circulation of the cleaning material, and that will reduce the expense of installation and up-keep to a minimum by the simplicity of construction of the coöperative elements.

A further object of the invention is to provide means for cooling the plates before they pass to the rolls, and also to furnish better ventilation to the operator.

50. To facilitate the understanding of the invention, the accompanying drawings are made a part of this specification, similar characters of reference being used to designate similar parts throughout the description and in the several figures of the drawings.

In the drawings Figure 1 is a vertical section through the table in direction of arrow *x* Fig. 2, showing the improved apparatus in elevation. Fig. 2 is a side view, showing the relative position of the apparatus to the cleaning roll mechanism. Fig. 3 is a plan of the upper drum, and Fig. 4 is a section on line 4-4, Fig. 1.

The apparatus is preferably constructed of sheet metal of suitable gage for stability, and comprises a hopper 1, adapted to be located beneath the cleaning roll mechanism 2. The hopper 1 is in open communication with the interior of a fan housing 3, in which is an exhaust fan 3^a. The fan is driven in the direction of arrow *a*, by any well known means, as illustrated in the drawings it is driven from a power shaft and pulley (not shown) through the medium of the belt 5 and the pulley 5^a, thus the function of the fan 3^a is to exhaust from the hopper 1. A conductor 4 provides an outlet from the fan housing 3, this conductor extends upward and is in open communication with the interior of a drum 6 located at a predetermined suitable elevation above the cleaning table and roll mechanism. The conductor 4 has an oblique connection with the drum 6, for the purpose hereinafter described. The lower or depending extension 6^a of the drum 6 is in the form of a truncated hollow cone, terminating in the neck 6^b, which in turn is in open connection with a distributing chamber 6^c. The distributing chamber is tapered down to a more or less narrow discharge opening 6^d located in juxtaposition to the cleaning rolls.

In operation, the hopper 1 is charged with the cleaning mixture, and the function of the fan draws the said mixture into the fan housing, from whence it is driven upward and obliquely into the drum 6. The oblique entrance into the drum under a forced draft imparts a swirling motion to the mixture as it passes downward through the neck 6^b into the distributing chamber 6^c, thereby causing a uniform discharge onto the rolls and plates through the opening 6^d. The cleaning rolls brush the mixture off of the plates and it is deposited into the hopper 1,

from whence the operation is repeated. Thus it will readily be seen that a continuous free circulation of the cleaning mixture may be kept up for any desired length of time, or until said mixture becomes 5 charged with the extraneous matter adhering to the plates when they are taken from the bath.

Exhaust from the drum 6 is utilized for 10 cooling and ventilating purposes by means of the conductor 7, being in open connection with the top of the chamber in the drum 6. The conductor 7 can be extended to any desired point to discharge the air onto the 15 plates, thereby cooling them and at the same time reducing the temperature in proximity to the operator.

The apparatus is anchored or supported 20 by suitable hangers and braces not shown in the drawings, but which are made to conform to the existing conditions of the structure in which it is installed.

The comparative weight, compactness, and 25 simplicity of construction of the improved apparatus are valuable factors from the standpoints of economy and durability.

The apparatus herein described and illustrated in the drawings is a simple embodiment of the invention, but the relative arrangement and the details of construction may vary more or less without departing 30 from the nature of the invention or the scope of the claims.

What I claim and desire to secure by Letters Patent is—

1. In apparatus for the purpose described, 40 a hopper adapted to be located beneath the cleaning roll mechanism, exhaust means connected with said hopper, an outlet conductor from said exhaust, an elevated drum, oblique connection between said drum and the outlet conductor, said drum being provided

with a discharge opening adapted to discharge onto the rolls.

2. In apparatus for the purpose described, 45 a hopper adapted to be located beneath the cleaning roll mechanism, exhaust means connected with said hopper, an outlet conductor from said exhaust, an elevated drum, oblique connection between said drum and the outlet conductor, a distributing chamber 50 connected with said drum, said distributing chamber being provided with a discharge opening adapted to discharge onto the rolls.

3. In apparatus for the purpose described, 55 a hopper adapted to be located beneath the cleaning roll mechanism, exhaust means connected with said hopper, a conductor extending upward from said exhaust, an elevated drum, oblique connection from the upper 60 terminal of the conductor to the drum, a distributing chamber located below the drum, a tapered connecting member between the drum and the distributing chamber, said distributing chamber being provided with a 65 discharge opening adapted to discharge onto the rolls.

4. In apparatus for the purpose described, the combination of a hopper located below 70 the cleaning roll mechanism, exhaust means connected with said hopper, an elevated circular receiving chamber, a connecting member between the exhaust means and the receiving chamber, the entrance from the connecting member to the chamber being at 75 an angle to the radius of said chamber, a distributing and discharge member located below the receiving chamber, and a tapered connecting member between said chamber and the distributing and discharge member. 80

WILLIAM GEORGE MOORE.
